BEACH BACK REST

Roy Olson, Hermosa Beach, Calif.

Application July 16, 1953, Serial No. 26,001

Term of patent 14 years

(Cl. D15—8)

Fig. 1

To all whom it may concern:

Be it known that I, Roy Olson, have invented a new, original, and ornamental Design for a Beach Back Rest, of which the following is a specification, reference being had to the accompanying drawing, forming a part hereof.

I claim:

The ornamental design for a beach back rest, substantially as shown.
